UNITED STATES PATENT OFFICE.

JAMES B. ROBINSON, OF CHATTANOOGA, TENNESSEE.

BUCKLE AND BAND HOOK.

1,416,417.

Specification of Letters Patent. Patented May 16, 1922.

Application filed July 21, 1920. Serial No. 398,027.

To all whom it may concern:

Be it known that I, JAMES B. ROBINSON, a citizen of the United States, residing at the city of Chattanooga, in the county of Hamilton and State of Tennessee, have invented certain new and useful Improvements in Buckles and Band Hooks, of which the following is a specification.

My invention belongs to that class of buckles and band hooks, which are used as part of the harness, to apply to the back band and to carry the traces.

The object of my invention is to produce a buckle and band hook of this character, which shall be cheap in manufacture, simple in construction and highly efficient in use.

It will not allow the trace or trace chain to injure the animal, will hold the trace in proper alignment, will prevent the trace from leaving its position and hold and lock it in position.

It is stamped from sheet metal and made smooth and rounded at its inner and outer edges, and is comfortable for the animal to wear, and it possesses a marked degree of utility.

It is an improvement on my Patent No. 726,763, dated April 28, 1903.

In the accompanying drawings, forming part of this specification:

Fig. 1, is an isometric view of my device, Fig. 2, is a plan view thereof,

Fig. 3, is a sectional view on the line 3—3 of Fig. 2,

Fig. 4, is a sectional view taken on the line 4—4 of Fig. 2, and

Fig. 5 is a sectional view taken on the line 5—5 of Fig. 2.

The body of the device is made up of the wide part 1 and the contracted part 2, made integral; in the part 1, I place the elongated slot 3 and in the part 2, I place the peculiar shaped slot 4.

The corners of the parts 1 and 2 are rounded as shown, and the corners of slots 3 and 4 are also rounded.

At each end of the body part 1, near the edges, I stamp a raised housing or bearing 5, into which fit the ends 7, of the tongue 6.

The longitudinal slot 3 is present to enable the folded band to extend through from the rear; the band is shown by dotted lines in Fig. 2 and is marked 8. The tongue 6 is arranged parallel to and in front of the said

slot 3 and extends through the fold of the band 8 and said tongue is arranged to move toward and from said slot, the rounded hollow bearings 5, allowing the ends of the wire to play, when it is being moved forward and backward; and on account of their shape and the marked degree of play allowed to the tongue 6, back bands of various thicknesses can be accommodated and are held tight against the wall of the hollow bearing, thus the band is held in an uniform, steady and desirable position at all times.

At the rear end of the slot 4, I place the hook 9, made materially wide at the base and rounded out and ending in a symmetrically shaped end, extending forwardly and downwardly in the slot 4. The slot 4 is narrowed toward its forward end as shown, and at its forward corners is provided with the upwardly flared wings, lips or extensions 10, said wings meeting in a rounded arch as shown. These wings or lips 10, keep the trace, which is hooked into and onto hook 9 from falling out or becoming loosened from the hook, and assist in holding the trace in alignment and desirable position.

The tongue 6 is usually made of wire and the portion extending across the slot 3 is crimped, so as to enlarge its bearings within the fold of the band, whereby said fold is expanded to greater thickness than the width of said slot to the end that the exterior faces of the band may be drawn against the metal at each side of said slot 3, whereby the band is prevented from passing through the said slot; the formation I employ, to wit: the arched bearings 5, in which the ends of the tongue 6 engage, gives the wire more play so as to cling close to the rear of the slot, which constitutes the holding qualities of the buckle; forming a more dependable and durable connection between the buckle and the band. In other words, the use of the tongue and the arched bearings in connection with the band, form a means for uniting the band to the buckle in a preferred manner, which adds greatly to the utility of the article.

The hook 9 and wings 10 are so arranged that the trace link or chain will not readily leave the hook 9; and by reason of the slot 4 being elongated at 15, enables me to insert the link laterally and then turn it, preventing its unlocking to a certainty.

I desire to be understood as claiming any modifications which fall with the scope of this specification and claim.

What I claim as new and my invention 5 and desire to secure by Letters Patent is:

In a buckle and band hook of the class described, a body part, a slot at one end thereof, movable means and arched bearings 10 for journaling the same, operating in connection with said slot, a second slot in said body part, the edge of said slot partly surrounded by holding means for engaging the

link of a trace, arched wings at the opposite end of said slot and at each side thereof, for retaining the trace link in alignment, 15 all the corners of said body part and the corners of the slots and of all the parts connected therewith, having rounded ends and corners.

In testimony whereof, I affix my signature 20 at Chattanooga, Tennessee, this 17th day of July, 1920.

JAMES B. ROBINSON.
